VAPORIZING FORCED DRAFT OIL BURNER

William Howard Frankland, Tampa, Fla.

Application May 2, 1949, Serial No. 90,822

7 Claims. (Cl. 158—91)

1

The present invention in general relates to oil burners of the type generally known as pot type burners, and more particularly to oil burners of the forced draft pre-vaporizing variety wherein the fuel oil is vaporized into gaseous form and mixed with a quantity of air immediately upon introduction into the oil burner to form a highly combustible mixture.

Pot type burners of the type heretofore in use are designed to effect conversion of the liquid fuel oil supplied to the oil burner to support combustion therein into a combustible gaseous mixture on introduction of the fuel oil into the burner, the process of being referred to in the art as "pre-vaporization." These burners, in general, comprise a metal pot or cylindrical receptacle, usually of sheet metal, with a top having an opening for the discharge of flames, and often having perforations in its sides. Oil is delivered to the bottom of the pot, and air under some pressure is delivered within a surrounding casing to enter the pot, as through the perforations in the side walls. The flame being started by ignition of liquid fuel oil upon the bottom, or other combustible material within the pot, fuel oil gas is generated by the heat radiated from the flame within the pot, and in part by heat conducted through the walls of the pot to the liquid oil upon the bottom; and thus the combustion continues. Such a burner is a very simple type of inexpensive construction, and has come into general use for such reasons. It is, however, inefficient in that the oil is not thoroughly gasified, and the flame generated is a yellow flame, indicating imperfect combustion and, therefore, loss of efficiency. The imperfect combustion characteristics in such burners is further indicated by deposits of carbon in and about the burners, such deposits being a common characteristic of this type of burner.

Burners have also been constructed to provide this pre-vaporization feature by means of a vaporizing chamber or pot into which the fuel oil inlet to the burner is coupled, which chamber is constructed of a highly thermoconductive material disposed in the portion of the burner in which combustion takes place. In this manner, the heat generated on combustion of the volatile mixture in the burner retains the material forming the walls of the vaporizing chamber at a sufficiently high temperature to vaporize the fuel oil immediately upon its introduction into the chamber and effect conduction of the vaporized oil through perforations into the combustion chamber, where it is mixed with sufficient quantities of air to create the combustible gas.

Initial lighting of the burner, from a "cold

2

start," is generally effected by a pilot or similar heat element disposed adjacent the vaporizing chamber, adapted to ignite liquid fuel oil overflowing from the chamber on to suitable cups or channels conveying the liquid fuel oil to a point adjacent the pilot or other igniting means.

A particular problem arises in connection with these prior art vaporizing oil burners, in that in many of such burners, the flame resulting from burning of the liquid fuel oil or of the vaporized gaseous fuel reaches the various fuel feed conducting outlets in the supply system within the oil burner, causing deposits of soot and other carbonized material about these elements and a reduction in the efficiency of the system by restricting ventilation and conduction of gases into the combustion chamber of the burner. This, in general, is due to the inability of the system to supply sufficient quantities of air during combustion of the liquid fuel oil after ignition of the burner to produce a "clean" flame of the type associated with substantially complete combustion of the fuel components. Many types of vaporizing oil burners have been known to blow up when ignited in a hot or gas generating condition, that is, when the burner is re-ignited a short time after it has just shut off operation. It is because of this tendency of the liquid or only partially vaporized fuel oil to produce large quantities of soot and other carbonized materials during combustion that many of the prior art oil burners provide for no supply of air to the pre-vaporizing chamber, the vaporized fuel oil being conducted into a separate combustion chamber where it is mixed with air to produce the combustible mixture. The air supplied to the combustion chamber in such burners, however, is generally not in proper quantity to effect substantially complete combustion of the fuel oil in both liquid and gaseous states and reduce carbon deposits on the elements of the burner to a negligible quantity.

Likewise, in many of the prior art vaporizing oil burners, since the vaporized or gaseous fuel is fed directly from the vaporizing chamber into the combustion chamber of the burner and immediately exposed to the flame, an insufficient time is available to permit an optimum mixture of air with the vaporized fuel, and the range of types of fuel oil which can be used in such burners is thereby severely restricted.

It is an object of the present invention to provide a fuel oil vaporizing burner which may be employed in fuel oil furnaces now in use to facilitate the generation of gas and liquid fuel oil and to insure complete combustion.

Another object of the present invention is the

provision of a fuel oil gas generator suitable for use in a pot type oil burner which may be readily adapted to any such type of burner now in commercial use, or which may be incorporated in or supplied with new burners of the pot type.

Another object of the present invention is the provision of a novel vaporizing oil burner adapted to generate a vaporized fuel oil and air mixture upon introduction of the fuel oil into the burner and conduct this mixture into the combustion chamber of the burner for further mixture with air in an appropriate quantity to insure complete combustion.

Another object of the present invention is the provision of a novel vaporizing oil burner wherein effective forced draft ventilation is provided in the vaporization and combustion sections of the burner to insure complete combustion during burning of either liquid or vaporized fuel substantially without carbonized combustion residue.

Another object of the present invention is the provision of a novel forced draft oil burner in which liquid fuel is vaporized and mixed with quantities of air insufficient to support combustion before introduction into the combustion chamber, and then mixed with additional quantities of air, characterized by substantially complete combustion of the fuel supplied thereto and high-efficiency operation.

Another object of the present invention is the provision of a novel vaporizing oil burner having a fuel oil vaporizing chamber of highly thermo-conductive material and adapted upon initial lighting of liquid fuel oil in the burner to produce a continuous ring of flame surrounding the chamber and rapidly heat the material to oil vaporizing temperature.

Other objects, advantages and capabilities of the present invention will become apparent from the following detailed description, taken in conjunction with the accompanying drawing showing only the preferred embodiment of the invention.

In the drawing:

Figure 1 is a vertical transverse section view of a vaporizing forced draft oil burner embodying the present invention; and

Figure 2 is a horizontal transverse section view taken along the lines 2—2 of Figure 1.

Referring to the drawing, wherein like reference characters designate corresponding parts throughout the several figures, the present invention includes a fuel oil burner, generally indicated at 10, adapted to provide a source of heat for a conventional furnace of the hot water or forced air types. The burner 10 is provided with a base 11 forming a substantially circular platform, preferably a casting of highly thermo-conductive material, in a horizontal plane and mounted adjacent the base of a furnace in the lower portion thereof by suitable brackets or other conventional mounting means (not shown).

Mounted on the circular base 11 of the burner is a vertically extending tubular shell forming a housing 12 defining the combustion chamber of the burner, indicated at 13. The lower periphery of the cylindrical shell 12 is adapted to fit snugly within an upstanding circular ring 14 provided on the base member 11 adjacent the outer periphery thereof and forming an oil retaining wall. The oil retaining wall 14 serves as a safety wall adapted to meet the requirements of the Underwriters' Code, and is of sufficient height to retain a sufficient quantity of liquid oil fuel within the

burner to prevent overflow of the oil from the burner should the burner fail to ignite. It is understood that a safety control valve is generally provided with the oil delivery system, of the float valve variety, which trips off before the oil reaches the upper edge of the oil retaining wall should the oil fail to ignite, and prevents further flow of oil into the burner.

Centrally located on the base member 11 within the combustion chamber 13 is a vaporizing chamber or pot, generally indicated at 15, adapted to effect vaporization of the liquid fuel oil introduced into the system into a gaseous form and mix the same with air before introduction into the combustion chamber 13. To this end, a raised circular platform 16 is provided on the upper surface of the base member 11, with its axis coincident with the axis of the burner base 11. The upper surface of the raised platform 16 may be provided with a series of concentric grooves, indicated at 17, about the upper surface thereof described about the central axis of the raised platform 16.

In the center of the raised platform 16 is an oil inlet opening 18 extending through the base member 11 concentric with the axis thereof. Coupled with the inlet opening 18 is a coaxial threaded aperture 19 extending through a portion of the base member 11 adapted to receive a threaded coupling 20, for removably coupling a fuel oil conduit 21 extending from a suitable fuel oil supply source (not shown) to the oil inlet opening 18.

A substantially cylindrical cup or hood 22 is provided, having a rim 23 forming the side of the chamber 15 of very slightly larger diameter than that of the raised platform 16 on the burner base 11, and is adapted to be slipped loosely over the edges of the raised platform 16. The top 24 of the hood 22 is substantially disk-shaped, and is provided with a central ventilating aperture 25 extending therethrough and disposed directly above the oil inlet hole 18 when the head 22 is in place about the raised platform 16. A plurality of ventilating apertures or conduits 26 are also provided in the top 24, spaced in a circular path near the outer edge of the housing 22 about a radius of the surface 24.

An asbestos endless circle wick 27 is fitted snugly about the outer wall of the hood 22 with the bottom edge of the wick resting upon the burner base 11 and the top edge of the wick being substantially flush with the top 24 of the vaporizing chamber hood 22. A circular groove 28 of the same diameter as that of the wick 27 may be provided in the upper surface of the burner base 11 underlying the lower edge of the endless wick 27 for purpose to be later described. A recess 29 is disposed about the rim 23 of the hood 22 adjacent the upper edge thereof, permitting the wick when disposed in surrounding relation to the hood 22 to be free from contact with the sides of the hood along the upper portion of the wick.

Hot wire ignition means is provided in the burner base 11, comprising a journal fitting 31 extending through the burner base 11 and having a tubular, partially threaded aperture extending therethrough adapted to receive and mount a hot wire igniter 32 having a high resistance wire 32' having a loop or coil 33 formed along the wire 32' disposed adjacent the upper edge of the inner circle wick 27 along a portion thereof to effect igniting of fuel oil absorbed by the wick 27 when the coil is energized. The hot wire

igniter 32 may be electrically coupled in a conventional manner across any suitable electric energy source (not shown).

Extending upwardly from the top 24 of the hood 22 and mounted thereon is a perforated tubular member 35 having longitudinally spaced series of perforations 36 extending through the walls thereof and axially directed laterally toward the combustion chamber 13. The lower-most group of perforations, generally indicated at 36', are preferably arranged on slightly downwardly inclined axes to direct jets of air across the edge of the wick 27 and toward the burner base 11. The upper portion of the tubular member 35 may be provided with an elbow coupling 37 or other suitable means connecting the upper edge of the tubular member 35 with the outlet of a blower or fan, indicated at 38, of any of the commercially marketed types, such as a small sirocco fan commonly employed in connection with forced draft burners.

Operation of the subject invention is substantially as follows: It is assumed, for purposes of this description, that a conventional thermostatically operated burner control valve is employed in conjunction with the burner, of the type having a bi-metallic control strip adapted to be heated by local electrically energized means, and which when heated, bends upward through a predetermined path. During its upward travel, it progressively actuates a switch in the energizing circuit of the blower or fan 38, and simultaneously closes the energizing circuit to the hot wire igniter 32. As the bi-metallic strip progresses in its upward movement, it then opens a fuel oil feed control valve in the feed line 21 to permit oil flow upward through the feed line and coupling fitting 20 and the oil inlet opening 18 onto the raised platform 16 of the vaporizing chamber 15.

The liquid fuel oil entering through the opening 18 and onto the raised platform 16, flows laterally between the loose fitting side or rim 23 of the vaporizing chamber hood 22 and the side of the raised platform 16 and along the bottom of the burner base 11 to the groove 28 underlying the endless circle asbestos wick 27.

The asbestos wick 27, when contacted by the oil, absorbs the oil rapidly, conducting it to the top of the wick immediately adjacent the loop or coil 33 formed in the energized hot wire lighter 32, where the oil is ignited. It will be apparent that the flame resulting from the burning oil will be confined to the upper edge of the endless circle wick 27 about the area where the wick is spaced from the sides of the hood 22, due to the recess about the edge thereof. A large supply of forced air is, at the same time, directed downwardly radially outward through the lower series of perforations in the tubular member 35 in the direction of the circle of flame from the burning oil extending about the upper edge of the endless circle wick 27. This supply of forced air is sufficient to support substantially complete combustion of the fuel oil so that the oil burns with a clean flame substantially free of carbonized residue. This likewise serves the purpose of directing the flame outwardly and downwardly from the upper edge of the endless circle wick 27 to cause very rapid heating of the burner base 11 to a sufficient temperature to cause immediate vaporization of the liquid fuel oil as it enters the vaporizing chamber 15 through the oil inlet opening 18 and contacts the upper surface of the raised platform 16. The concentric circular

grooves 17 provided in the upper surface of the raised platform 16 increase the surface of the raised platform which the fuel oil is brought into contact with to facilitate rapid vaporization of the oil.

Simultaneously with the conversion of the liquid fuel oil into a gaseous state due to the high temperature of the raised platform 16, oxygen is mixed in the chamber 15 with the vaporized fuel oil, air being forced by means of the fan 38 downwardly through the tubular member 35 and the central opening 25 in the top 24 of the hood 22 to effect pre-mixing of the vaporized fuel oil with air in an insufficient quantity to support combustion. The mixture of vaporized fuel oil and air is conducted through the series of openings 26 in the top of the vaporizing chamber 15 and into the combustion chamber 13 where the same is ignited by the flame occurring on combustion of the liquid fuel oil absorbed by the endless circle wick 27. The mixed air and vaporized fuel oil is forced outward through openings 26 and into the combustion chamber by the pressure generated in the vaporizing and mixing chamber 15 by the forced air directed downwardly through the tubular member 35 and aperture 25. Combustion within the chamber 13 will be readily sustained by the continuous supply of mixed air and vaporized fuel oil forced through the openings 26, after the liquid fuel oil absorbed by the asbestos wick 27 has been exhausted through combustion.

While but one particular embodiment of the invention has been particularly shown and described, it is distinctly understood that the invention is not limited thereto but that various modifications may be made without departing from the spirit and scope of the invention, and it is desired, therefore, that only such limitations shall be placed thereon as are imposed by the prior art and are set forth in the appended claims.

What is claimed is:

1. In a burner, the combination of a burner base plate and a liquid fuel delivery passage having an outlet in said base plate, enclosure means defining with said base plate a gas generating chamber disposed in surrounding relation to said outlet, second enclosure means disposed in surrounding relation to the first enclosure means defining an upwardly opening combustion chamber, forced draft generating means having an elongated conduit extending through said second enclosure means and coupled to said first enclosure means for delivering air downwardly through a restricted orifice in said first enclosure means disposed oppositely of said fuel outlet to form a downwardly directed jet directed toward said outlet for mixing air with the gas generated therein, a plurality of apertures formed in said first enclosure means and spaced outwardly from said elongated conduit to deliver the mixture of gas and air from said gas generating chamber in upwardly directed jets, said elongated conduit having a vertically arranged series of perforations delivering additional quantities of air into said combustion chamber in the form of outwardly directed jets intercepting said upwardly directed jets for further mixture with the mixed air and gaseous fuel to generate a combustible mixture.

2. In a burner, the combination of a burner base plate of highly thermoconductive material, a liquid fuel delivery passage coupled thereto having an outlet orifice disposed in said base

plate, hood means disposed in surrounding relation to said orifice forming with said base plate a gas generating enclosure, means extending from said burner base forming a combustion chamber surrounding said gas generating enclosure, forced draft means for delivering air downwardly through a restricted orifice in said hood means into said gas generating enclosure for mixture with the gas generated therein, an annular series of apertures formed in the top of said hood means and spaced outwardly from said forced draft means to deliver the mixture of gas and air from said gas generating enclosure to said combustion chamber in upwardly directed jets, and said forced draft means having apertures for delivering air laterally in radially directed jets into said combustion chamber intercepting said upwardly directing jets in sufficient quantity to form a combustible mixture, an endless fuel absorbent wick disposed in surrounding relation to said hood means, means providing passage for liquid fuel from said exit orifice to said wick, and igniter means disposed adjacent said wick to ignite liquid fuel oil absorbed thereby, whereby a ring of ignited fuel oil is provided on initial lighting of said burner entirely surrounding said gas generating enclosure, at least some of said forced draft jets being arranged in outwardly and downwardly inclined directions across said wick and toward said burner base plate to facilitate heating of said burner base plate to a fuel vaporizing temperature.

3. In a burner, the combination of a burner base plate of highly thermoconductive material capable of supporting a film of fuel, a liquid fuel delivery passage coupled thereto having an outlet orifice disposed in said base plate, hood means disposed in surrounding relation to said orifice forming a gas generating enclosure, means extending from said burner base forming a combustion chamber surrounding said gas generating enclosure, forced draft means including a tubular elongated conduit for delivering air downwardly through a restricted orifice in said hood means into said gas generating enclosure for mixture with the gas generated therein, an annular series of apertures formed in the top of said hood means spaced outwardly from said elongated conduit to deliver the mixture of gas and air from said gas generating chamber to said gas chamber in upwardly directed jets, said elongated conduit having a vertically arranged series of apertures for delivering air in radially directed jets into said combustion chamber intercepting said upwardly directing jets in sufficient quantity to form a combustible mixture, an endless fuel absorbent wick disposed in surrounding relation to said hood means, means providing passage for liquid fuel from said exit orifice to said wick, and igniter means disposed adjacent said wick to ignite liquid fuel oil absorbed thereby, whereby a ring of ignited fuel oil is provided on initial lighting of said burner entirely surrounding said gas generating enclosure, the lowermost of said series of apertures in said elongated conduit being arranged along radially and outwardly inclined axes to provide jets of air across said wick and toward said burner base plate to facilitate heating of said burner base plate to a fuel vaporizing temperature.

4. In a burner, the combination of a highly thermoconductive burner base plate capable of supporting a film of fuel, a liquid fuel delivery passage coupled thereto having an outlet orifice disposed in said base plate, cylindrical hood means of highly thermoconductive material dis-

posed in surrounding concentric relation to said orifice forming a gas generating enclosure, means extending from said burner base forming a combustion chamber surrounding said gas generating enclosure, forced draft means including a tubular elongated conduit for delivering air downwardly through a restricted orifice in said hood means axially aligned and disposed oppositely relative to said fuel outlet to form a downwardly directed jet intercepting said fuel outlet for mixture with the gas, an annular series of openings formed in said hood means adjacent and immediately outwardly of said elongated conduit for directing the vaporized gas mixture from said gas generating enclosure to said combustion chamber in the form of upwardly directed jets, said elongated conduit having a vertically arranged series of apertures for delivering air in radially directed jets into said combustion chamber intercepting said upwardly directed jets to form a combustible mixture, an endless fuel absorbent wick disposed in surrounding relation to said hood means, means providing passage for liquid fuel from said exit orifice to said wick, and igniter means disposed adjacent said wick to ignite liquid fuel oil absorbed thereby, whereby a ring of ignited fuel oil is provided on initial lighting of said burner entirely surrounding said gas generating enclosure, the lowermost of said series of apertures in said elongated conduit being arranged along downwardly inclined radial axes to provide radial jets of air extending across said wick and directing the flame thereon toward said burner base plate to facilitate heating of said burner base plate to a fuel vaporizing temperature.

5. In a burner, the combination of a highly thermoconductive burner base plate capable of supporting a film of fuel, a liquid fuel delivery passage coupled thereto having an outlet orifice disposed in said base plate, hood means of highly thermoconductive material disposed in surrounding relation to said orifice forming a gas generating enclosure, means forming a combustion chamber surrounding said gas generating enclosure, forced draft means including a tubular elongated conduit for delivering air downwardly through a restricted orifice in said hood means into said gas generating enclosure for mixture with the gas, a plurality of apertures formed in the top of said hood means and spaced outwardly from said elongated conduit to deliver the mixture of gas and air from said gas generating chamber to said combustion chamber in upwardly directed jets, said elongated conduit having a vertically arranged series of apertures for delivering air in radially directed jets into said combustion chamber intercepting said upwardly directed jets to form a combustible mixture, an endless fuel absorbent wick disposed in surrounding relation to said hood means, means permitting flow of the liquid fuel from said exit orifice to said wick, and igniter means disposed adjacent said wick to ignite liquid fuel oil absorbed thereby, whereby a ring of ignited fuel oil is provided on initial lighting of said burner entirely surrounding said gas generating enclosure, the lowermost of said series of apertures in said elongated conduit being disposed immediately adjacent the upper extremity of said hood means and arranged to provide radial jets of air directing the flame from the ignited fuel on said wick outwardly and downwardly toward said burner base plate to facilitate heating of said burner base plate to a fuel vaporizing temperature.

6. In a burner, the combination of a burner base plate of highly thermoconductive material, a cylindrical housing disposed on said base plate forming therewith a gas generating chamber, a liquid fuel delivery passage having a feed outlet formed in said base plate and opening into said cylindrical housing along the axis thereof, tubular means disposed on said base and surrounding said cylindrical housing to define a combustion chamber, a restricted orifice forming an air delivery opening in said cylindrical housing axially aligned and oppositely disposed relative to said fuel outlet, forced draft generating means having an elongated conduit extending through said combustion chamber for delivering a forced draft of air downwardly through said restricted orifice to agitate vaporizing the fuel admitted through said outlet and mix air with gas generated in said chamber, an annular series of apertures formed in the top of said cylindrical housing spaced outwardly from said elongated conduit to deliver the mixture of gas and air from said gas generating chamber to said combustion chamber in upwardly directed jets, said elongated conduit having a vertically arranged series of apertures for delivering air in radially directed jets arranged in horizontal planes perpendicular to said jets of mixed gas and air into said combustion chamber.

7. In a burner, the combination of a burner base plate and a liquid fuel delivery passage having an outlet in said plate, cylindrical enclosure means defining a gas generating chamber disposed in surrounding concentric relation to said outlet, second enclosure means disposed in surrounding relation to the first enclosure means defining a combustion chamber, forced draft generating means having an elongated conduit ex-

5
